ROLL CRUSHER FOR PRODUCING CUBICAL SHAPED FRAGMENTS

Arthur M. Grasse, Chicago, Ill., assignor to Goodman Manufacturing Company, Chicago, Ill., a corporation of Illinois

Application February 3, 1953, Serial No. 334,928

11 Claims. (Cl. 241—236)

This invention relates generally to rock crushers and more particularly to an improved crusher capable of producing essentially cubical shaped fragments, and characterized by substantial freedom from dust in the crushing process.

Specifications for crushed rock used in Portland cement and bituminous concrete are now characterized by provisions that substantially all of the material shall be essentially cubical in form with the amount of splinter-like material at a minimum. Efforts to reduce the amount of such splinter-like material by the employment of crushers having crushing rolls of concave-convex configuration have not been entirely successful because of the excessive amount of dust created in the crushing operation. The presence of such dust as a coating upon the crushed aggregates is objectionable as it prevents good bond of the cement with the aggregates.

According to the present invention, mating rolls move at the same peripheral speed along their entire line of conjugation which is the line through the center of the rolls containing the nip or point of closest approach of the rolls to each other. It is therefore possible completely to avoid the above-mentioned dust-producing rubbing action upon the rock fragments caused by differential peripheral speeds in concave-convex rolls, yet at the same time enabling the rock to be crushed into the desirable substantially cubical fragments described. In carrying out the invention a pair of identical cylindrical crusher rolls are provided with interdigitating lands or corrugations. These lands describe smooth continuous curves along the cylindrical faces, so that as the rock is crushed between the interdigitating lands, the curvature of the lands prevents any substantial formation of splinter-like fragments.

The form of the curve in the lands on each crusher roll is not critical, and the form may be that of circular arcs described on a developed surface of the cylinder of such roll. The curves however may be in the form of nested ellipses, or the portions of an hyperbola or parabola having sharply changing radii. In fact, any sinuous curve may be described by the lands on each cylinder, as long as the rolls are conjugate and as long as the lands interdigitate and as long as the instantaneous distance or spacing between mating lands on opposite rolls is the same across the entire length of the rolls as the lands pass the line of conjugation.

With the foregoing considerations in mind it is a principal object of the invention to provide a roll crusher characterized by producing discrete rock particles of substantially cubical configuration, and characterized in its operation by the absence of dust.

Another object is to afford a roll crusher assembled with identical crushing rolls, each of said rolls having lands thereon which curve along the curving surface of the roll, and which when the rolls are coating function to crush the rock into substantially cubical fragments only.

Other objects and important features of the invention will become apparent from a study of the following specification taken with the drawings which together show a preferred embodiment of the invention and what is now considered to be the best mode of practicing the principles thereof. Other embodiments may be suggested to those having the benefit of the teachings herein, and it is therefore intended that the scope of the invention not be limited by the precise embodiment herein shown, nor otherwise than by the spirit and purview of the claims subjoined.

2

In the drawings:

Fig. 1 is a top plan view of a roll crusher, having embodied therein the improvements according to the present invention;

5 Fig. 2 is a side view of the crusher shown in Fig. 1 showing the gear train for driving the crusher rolls;

Fig. 3 is an enlarged end view of a portion of the crushing rolls shown in Fig. 1;

Fig. 4 is a developed view of a portion of the crusher 10 rolls shown in Fig. 3 taken along the line 4—4 of Fig. 3, and showing how the curved lands of each of the rolls interdigitate at the line of conjugacy;

Fig. 5 is a reduced in scale developed view of one of the crusher rolls showing one method by which the lands 15 may be constructed, if desired;

Fig. 6 is an enlarged sectional view taken along the line 6—6 of Fig. 1 showing the crushing action taking place along the surface of the rolls as the lands turn with the rolls and approach the line of conjugacy; and

20 Fig. 7 is a sectional view taken along the line 7—7 of Fig. 1 showing a means for adjusting the distance between the rolls in accordance with the desired size of the crushed rock.

Referring now particularly to Figs. 1 and 2 of the 25 drawings, the improved roll crusher according to the present invention is indicated generally by the reference numeral 10, and includes a pair of spaced side frames 11 and 12 which are held in spaced relationship by end frame members 13 and 14. The spaced frames 11 and 12 support respectively bearing standards 16 and 17 having a main drive shaft 18 turning therein. A drive pulley 19 is made fast to the drive shaft 18 at one end thereof, and is driven by a belt 21 connected to any convenient prime mover.

25 A driving pinion 22 is made fast to the opposite end of the drive shaft 18 and meshes with a bull gear 23 made fast to a crusher roll shaft 24 supported in bearing standards 26 and 27 mounted respectively on the frame members 11 and 12.

30 A crusher roll 28 is made fast to the crusher roll shaft 24 and is in interdigitating relationship with a similar crusher roll 29 made fast to a shaft 31 supported in movable bearing standards 32 and 33, mounted respectively in slideways 34 and 36 positioned on top of the spaced side frame members 11 and 12 respectively.

35 40 The two crusher rolls 28 and 29 are arranged to turn in opposite directions in synchronism by means of an idler pinion 37 meshing with the bull gear 23 and arranged to turn on a stub shaft 38 extending from the side frame member 12. The idler pinion 37 meshes with an idler pinion 39 supported on a stub shaft 41 held in a pair of arms 42 and 43 embracing the pinion 37 therebetween.

45 50 The pinion 39 is held in meshing engagement with a bull gear 43 similar to the bull gear 23 and fast to the shaft 31 supporting the crusher roll 29 which is complementary to the crusher roll 28. As seen in Fig. 2 the pinion 39 is held in such meshing engagement with the bull gear 43 and by a pair of arms 44 and 46, one end of each of such arms being supported upon the roll shaft 31.

55 60 It will be seen that the bull gear 43 may be moved towards or away from the bull gear 23 while the two are driven at identical speeds but in different directions.

The crusher roll 29 is arranged to be moved to or from the crusher roll 28 according to the size of the material to be crushed therebetween, and to this end each

65 70 of the guideways 34 and 36 is provided with a vertically movable wedge 47 which coacts with a fixed wedge surface 48 of the guideways 34 and 36 and a movable wedge surface 49 which is movable with the sliding bearing supports 32 and 33. The wedge 47 is locked into position by an adjusting nut 51 threaded to a stud 52 extending from the upper side of the wedge 47 and through the upper part of the guideways 34 and 36. It will thus be seen that the wedges 47 position the rolls 28 and 29 a desired distance apart according to the desired size of the crushed material.

75 The two rolls 28 and 29 are adapted to move apart to accommodate the presence of tramp iron or other material not capable of being crushed by the rolls, so that the rolls 28 and 29 will not become damaged.

To this end each of the shiftable bearing supports 32

and 33 are arranged to move against the force of a pair of spiral compression springs 53, one end of which is bottomed against the shiftable bearing 32 or 33 and the other end bearing against an abutment 54 which is adjusted in its position by an adjusting screw 56 threaded into the end spacer member 14.

According to the present invention the crusher rolls 28 and 29 are constructed so as to have lands 57 which extend in a smooth continuous curve for the length of the roll as seen more clearly in Fig. 4, which view is developed from a portion of the crusher roll 29. The precise form in cross section of each of the lands 57 is not important to the invention, nor is the precise form of the curve that each such land takes throughout the length of either of the crusher rolls, but it is important that all portions of the curve upon which such lands lie have in the case of a smooth continuous curve, a radius between L and $3/2$ L, and, in the case of a curve having constantly changing radii, each of the radii between L and $3/2$ L where L is the length of the roll, so that at the line of conjugacy which is the line through the center of the crushing rolls containing the nip or the point of closest approach of the rolls to each other, of the complementary rolls 28 and 29 no opportunity will be afforded for the presence between such interdigitating lands of elongated or needle-like fragments. As seen in Fig. 4, a fragment of rock caught between a pair of interdigitating ribs 57 at or near their line of conjugacy is broken into a number of essentially cubical shaped fragments F. As seen in Fig. 6, larger fragments of rock F2 are "nipped" or caught between the lands 57 as they converge towards each other, so that when the lands approach the line of conjugacy the fragments F2 will have been broken into the smaller particles F as seen in Fig. 4.

Referring now to Fig. 5, there is shown a reduced in scale developed view of one of the crushing rolls 28 or 29. This view is merely for the purpose of illustrating one method whereby the lands 57 may be laid out on such crushing roll. As seen in this view, the crushing roll has a length L, and the lands 57 are laid out on such developed surface on arcs having a radius between limits, by way of example of L to $3L/2$. Each of such lands 57 may be separated from each other any suitable distance, which for purposes of explanation herein is called the pitch distance, PD. As seen in Fig. 6, the dimensions of each land 57 and the distance between each is such that as the rolls 28 and 29 rotate in synchronism, a desired distance is maintained between the rolls 28 and 29 at their line of conjugacy, which distance may of course be varied by the setting of the wedges 47.

It will be noted from the foregoing description that the crusher rolls 28 and 29 are identical in shape. It will be noted also that the two rolls turn with identical peripheral speeds. Since the two rolls turn with identical speeds there will be no rolling or sliding action of a rock fragment caught by the rolls, as would be the case where the rolls are of concave-convex configuration. Because of the fact that the rolls turn at the identical peripheral speed there will be no abrading of the rock fragments with the consequent substantial elimination of dust.

Since the rock being fragmented by the cooperating rolls is caused always to distribute itself in arcuate or curving channels defined by the curving of the lands 57, and defined also by the presence in such space between contiguous lands of a land of the cooperating roller, particularly at the line of conjugacy thereof, all such particles of rock will be caused to be fragmented at such line of conjugacy in substantially cubical fragments, at the same time with the elimination of dust.

The spacing or distance C (Fig. 3), between the mating lands 57 on the opposite rolls 28, 29 is the same across the entire length of the rolls so as to produce a uniformly-crushed size of cubical particle all the way across the rolls. The distance or spacing C is measured between the sides of the opposed lands as the lands pass the line of conjugation and the distance or spacing C is preferably substantially a number of times greater than the nip. The distance C is the same throughout the entire length of the rolls as a result of employing a uniform pitch distance PD, Fig. 5, and uniform thickness of land across the entire length of the rolls with identical curves of the land on each of the rolls.

While the invention has been described in an embodiment where the cooperating lands 57 of the mating rolls

28 and 29 are constructed as arcs of a circle upon the developed surface of each cylindrical roll, it is contemplated also that such ribs be drawn on curves which are parts of an ellipse particularly at the parts of such ellipse where radius is changing at its greatest rate, or as parts of an hyperbola or a parabola, particularly at portions of such curves where the radius of curvature is changing at its greatest rate.

While the invention has been described in terms of a preferred embodiment thereof, it is intended that the invention shall include all such other forms which have been alluded to, or which fall within the equivalents of such other forms. The scope of the invention, therefore, is not intended to be limited by the precise embodiment herein shown, nor otherwise than by the scope and purview of the claims here appended.

I claim as my invention:

1. In a roll crusher, a pair of cylindrical rolls having cooperable outer crushing surfaces, each of said roll surfaces having interdigitating lands thereon, each of said lands being generated as segments of curves each having a radius between L and $3/2$ L where L is the roll length, said curves being symmetrical to a plane bisecting each of said rolls and normal to the axis of rotation thereof and extending in a smooth continuously curving path along the length of its roll, a mounting for spacing said rolls a predetermined distance apart, and means for synchronizing the speeds of said rolls to maintain said lands in interdigitating relationship but out of contact with each other.
2. In a roll crusher, a pair of cylindrical rolls having cooperable outer crushing surfaces, each of said roll surfaces having interdigitating lands thereon, each of said lands being generated as a curve having continuously sharply changing radii on a developed surface of each of said rolls and extending in a continuously curving path along the length of its roll each of said radii of said curve having a magnitude of between L and $3/2$ L where L is the length of its roll, a mounting for spacing said rolls a predetermined distance apart, and means for synchronizing the speeds of said rolls to maintain said lands in interdigitating relationship but out of contact with each other.
3. In a roll crusher, a pair of identical rolls having cooperable outer crushing surfaces and identical peripheral speeds, each of said roll surfaces having interdigitating lands thereon, each of said lands being identical and extending along the length of its roll in a continuously curving path having continuously sharply changing radii, each of said radii having a magnitude between L and $3/2$ L where L is the length of the roll, a mounting for spacing said rolls a predetermined distance apart, and means for synchronizing the speeds of said rolls to maintain said lands in interdigitating relationship but out of contact with each other.
4. In a roll crusher, a pair of identical crusher rolls having cooperable outer crushing surfaces and identical peripheral speeds, each of said crushing surfaces having interdigitating lands thereon, each of said lands extending in a continuously curving path along the length of its roll, said path having a radius between L and $3/2$ L where L is the length of the roll, a mounting for spacing said rolls a predetermined distance apart, and means for synchronizing the speeds of said rolls to maintain said lands in interdigitating relationship but out of contact with each other.
5. In a roll crusher, a pair of rolls having cooperable outer crushing surfaces, both of which are cylindrical, said roll surfaces comprising a plurality of interdigitatingly intermeshing teeth, each of said teeth extending in a continuously curving path across the length of its roll, the teeth on each roll having uniform thickness and uniform pitch across the length of the roll, a mounting for spacing said rolls a predetermined distance apart, and means for synchronizing the speeds of said rolls to maintain the teeth in interdigitating meshing relationship but out of contact with one another.
6. The structure defined in claim 5, wherein the pair of rolls are identical.
7. The structure defined in claim 5, wherein the diameters of the pair of cylindrical rolls are the same.
8. The structure defined in claim 5, wherein the pair of rolls have the same peripheral speed.
9. The structure defined in claim 5, wherein all teeth on both rolls are identical.

10. In a roll crusher, a pair of identical rolls having cooperable outer crushing surfaces and identical peripheral speeds, each of said crushing surfaces comprising a plurality of interdigitating identical lands each extending in a continuously curving path along the length of its roll with each of the lands having uniform thickness and uniform pitch throughout the full length thereof, a mounting spacing said rolls a predetermined distance apart, and means synchronizing the speeds of said rolls to maintain said lands in interdigitating relationship but out of contact with each other.

11. In a roll crusher, a pair of rolls having cooperable outer crushing surfaces, both of which are cylindrical, each of said roll surfaces having interdigitating lands thereon, each of said lands extending in a continuously curving path along the length of its roll, the lands on each roll having uniform thickness and uniform pitch across

the length of said rolls, a mounting for spacing said rolls a predetermined distance apart, and means for synchronizing the speeds of said rolls to maintain said lands in interdigitating relationship but out of contact with each other.
